UNITED STATES PATENT OFFICE.

FRANK JOSEPH SUCHANEK, OF NEW YORK, N. Y.

HYDROTHERMOMETER.

1,054,879.

Specification of Letters Patent.

Patented Mar. 4, 1913.

Application filed May 21, 1912. Serial No. 698,783.

To all whom it may concern:

Be it known that I, FRANK J. SUCHANEK, a citizen of the United States, residing at New York, in the county of New York and 5 State of New York, have invented certain new and useful Improvements in Hydro-thermometers, of which the following is a specification, reference being had therein to the accompanying drawing.

10 This invention relates to hydro-thermometers, and the principal object of the invention is to provide a device of the character described by means of which the density and temperature of a liquid can be ascertained 15 without the liquid being exposed to the outer air for any considerable length of time. This is accomplished by mounting a thermometer and a hydrometer in a transparent body portion into which the liquid 20 is sucked by means of a rubber bulb, the spout of the hydro-thermometer being thrust into the bottle or other receptacle containing the liquid, and the bulb released so that upon 25 releasing the bulb the liquid will be sucked into the glass body portion of the hydro-thermometer.

This invention is illustrated in the accompanying drawings, wherein:—

Figure 1 is a sectional view through the 30 device. Fig. 2 is a section along the line 2 2 in Fig. 1. Fig. 3 is a section along the line 3 3 in Fig. 1.

Referring to the accompanying drawings, it will be seen that this device comprises the 35 glass body portion having the neck 10, the enlarged base portion 11, and the reduced spout 12. Rubber diaphragms 13 which are provided with the perforations 14, are mounted in the neck 10 and form a compartment in which the hydrometer 15 is 40 mounted, the hydrometer being of the usual construction. A thermometer 16 passes through openings 17, formed in the diaphragms and has its lower portion extending beneath the diaphragm 13. A rubber bulb 18 surrounds the neck 10 and is prevented from slipping off by the flanged end 19 of the neck, the flanged end of the neck fitting into the bulb as shown in Fig. 1.

When using this device, the rubber bulb 50 is compressed so that the air is forced out of the device and the spout 12 is inserted into the bottle and the bulb then released so that a suction is caused through the body portion thus sucking the liquid in the bottle 55 up into the device to approximately the point indicated in Fig. 1. It will thus be seen that the thermometer which has its base portion immersed in the liquid, will register the temperature and the hydrometer will 60 float in the liquid and indicate the density. After the temperature and density of the liquid have been ascertained, the bulb 18 is compressed and this forces the liquid back into the bottle, after which the device may 65 be removed and the stopper of the bottle replaced. It will thus be seen that the only times when the contents of the bottle will be exposed to the air will be during the removal and replacing of the cork, which is 70 for comparatively short lengths of time.

Having thus described my invention, what I claim is:—

1. A device of the character described, comprising a transparent body portion, perforated diaphragms mounted in said body portion, a hydrometer mounted in said body portion between said diaphragms, a thermometer passing through said diaphragms, and means for sucking liquid into 75 said body portion.

2. A device of the character described, comprising a body portion having a reduced neck, perforated diaphragms mounted in said neck, a hydrometer mounted in said 80 neck between said diaphragms, a thermometer passing through said diaphragms, and means for sucking liquid into said body portion.

In testimony whereof I hereunto affix my 90 signature in presence of two witnesses.

FRANK JOSEPH SUCHANEK.
